SOFA BED

Rudolph O. Smith, Milford, Conn., assignor to
The Owen Silent Spring Company, Inc., Bridge-
port, Conn., a corporation of Connecticut

Application June 17, 1938, Serial No. 214,203

4 Claims. (Cl. 5—21)

This invention relates to sofa beds and has for its general object the provision of an extensible or sliding bed section for a sofa which does not necessitate modification of the general characteristics, construction and appearance of the sofa.

Other objects of my invention are the elimination of the objectionable features of prior constructions and include the elimination of the use of a third mattress, the provision of a sofa bed which is comfortable for sitting and sleeping and at the proper height for both, elimination of the relatively wide concealing member or false rail at the front of the sofa bed, and the use of a narrow false rail or concealing member the lower edge of which will be aligned with the rails of the frame of the sofa bed and still conceal the slideable bed section under the sofa. This construction provides also for exposing the legs of the sofa bed so that in all appearances the sofa bed will look like an ordinary sofa in which no sliding bed section is provided.

It is also an object of my invention to provide improved means connecting the guiding means to the sliding bed section and the sofa. It is also an object to improve the construction generally so that the sliding bed section may be provided with simplified and inexpensive supporting legs and readily accessible operating means may be employed for spreading the legs and raising the bed and said operating means may function to prevent the accidental lowering of the bed.

Another object of my invention is to so construct the various parts that it will not be necessary to use relatively stiff or highly compressed springs in the platform or sofa seat and the removable mattress to obtain the proper sitting height and so that the sleeping comfort of the sofa seat will be substantially the same as that of the removable mattress which is swung onto the sliding bed section, and also that the sofa when used for sitting will provide a comfortable seat with the combined effect of the readily yieldable springs of the platform seat and of the removable mattress.

It is another object of my invention to make provision for lowering the rear edge of the sliding bed section closer to the floor, to permit the use of an inclined support for the platform seat and the proper positioning of the false front rail with such inclined construction.

Other objects of the invention will appear from the following description taken in connection with the drawings, in which—

Fig. 1 is a vertical transverse section taken just inside of the arm at one end of the sofa showing the sliding bed section in end view and parts of the platform or sofa seat and removable mattress broken away;

Fig. 2 is a view similar to that of Fig. 1 showing the sliding bed section pulled out of the sofa and in raised position and the removable mattress on said sliding bed section;

Fig. 3 is a horizontal section taken through the rails or main frame of the sofa and shows a top view of the sliding bed section in the position shown in Fig. 2;

Fig. 4 is a detailed view showing a supporting leg of the sliding bed section;

Fig. 5 shows my invention embodied in a sofa provided with a back only;

Fig. 6 shows my invention embodied in a sofa or couch not provided with either arm rests or a back;

Fig. 7 is a view similar to that of Fig. 2 showing a modification; and

Fig. 8 is a view similar to that of Fig. 1 of the modification shown in Fig. 7.

For purposes of disclosure, I have shown in Figs. 1 to 6 a substantially conventional form of sofa which includes the usually strong, sturdy frame construction as indicated in the various figures. The sofa frame comprises a front rail 10, a rear rail 11, and end rails 12. Rear legs 13 are connected to said rails by any suitable means as indicated in Fig. 3, said legs having portions which form the framework for the back 14 of the sofa to which framework are secured arms 15 supported on the end rails 12. These arms may be suitably covered.

The sofa includes a platform seat or mattress 18 which is suitably supported on the frame of the sofa and which includes spring inserts 40 or springs 19 which are relatively long and yieldable and any suitable filling material 20 between the upper ends of the springs and the cover of the platform seat. As will appear later the height of the platform seat is such that a mattress 22 may be supported thereon to provide a seat at standard sitting height when the sofa is used for sitting. This mattress includes spring inserts comprising springs 23 which are also relatively long and yieldable and spaced from the cover of the mattress by any suitable filling material 24 and 25.

As disclosed in Fig. 1 the front rail 10 is located higher than the rear rail 11 to provide a space through which the sliding bed section 25 may be moved into and out of position under the

sofa. The front legs 26 may be secured to the end rails by any suitable means. The construction is such that the lower edges of the side and rear rails and of a false front rail 27 are spaced at a suitable distance from the floor to display the legs of the sofa as in the conventional sofas.

The false rail or concealing member 27 is connected to the front angle member 28 of the sliding bed 25 which includes side angle members 29 and 30 and a rear angle member 31, all of said angle members being secured together in the relation indicated to form the frame of the sliding bed section, said angle members being perforated for anchoring elements of a flat spring 32 of any conventional form.

The sliding bed section 25 is supported by front legs 35 and rear legs 36 on which are mounted casters 37, the legs being pivoted to the downwardly extending flanges of the angle bars 29 and 30 of the frame of the sliding bed section as indicated at 38 and being connected by a brace 39 pivotally connected to an L-shaped bracket 40 secured to the horizontal front or rear angle bar 28 or 31 as the case may be. The lower end of the supporting bracket 39 is connected to the leg by a pin 54 by which operating links 41 and 42, Fig. 1, are pivotally connected to the legs 35 and 36. The operating links at one end of the bed are pivoted to an arm 43 of an operating bail which comprises an operating bar 44 and another arm 45 at the other end of the sliding bed section to which the other operating links are connected. Said arms are connected to the side members 29 and 30 by pivot pins 60 located intermediate of the pivot pins which connect the links 41 and 42 to the arms 43 and 45.

When it is desired to use the sliding bed section, it is drawn forwardly from the position shown in Fig. 1 to the position shown in Figs. 2 and 3 and is guided in this forward movement by a pair of bars 46 and 47 pivotally connected together, the corresponding ends of said bars at one end of the sliding bed section being pivotally connected to brackets 48 and 49 on the rear bar 31 of the sliding bed section and on the rear rail 11 of the sofa.

The other ends of the bars 47 and 46 are connected by pin and slot connections 50 and 51 to brackets 52 and 53 connected respectively to the rear bar 31 and the rear rail 11, Fig. 3. The brackets 48 and 52 extend below the frame of the sliding bed section, and the pivotal and sliding connections between the bars 46 and 47 and all of the brackets are such that the bars 46 and 47 may adjust themselves angularly vertically as the sliding bed section is moved. As the bars 46 and 47 cooperate with the frame of the sliding bed section, it is obvious of course that their connection with the sofa and sliding bed section will limit the outward movement of the sliding bed section, so that it will be automatically stopped in the proper position adjacent to the sofa to be then elevated by the means heretofore described, into the position shown in Fig. 2. The connections between the front ends of the bars 46 and 47 and the rear bar 31 of the sliding bed section are preferably such that the bars may be disconnected from the sliding bed section by raising their front ends. The sliding bed section may then be moved to another part of the room to be used as a separate bed.

The construction is such that the legs assume the angular relation to each other shown in Fig.

2 when the sliding bed section is raised into bed height position.

This provides a stable construction. Spreading of the legs is prevented by the links 41 and 42. Any tendency of the pair of legs 35 to swing inwardly is opposed by the work required to swing the pair of legs 36 inwardly under the weight of the bed and occupant. Such movement would swing the bail clockwise and would be limited by the limited movement of the bail in a clockwise direction as is obvious from Fig. 2. Swinging movement of the pair of legs 36 beyond the position shown in Fig. 2 is prevented by engagement of the operating bar of the bail with stops, as indicated.

The construction in Figs. 1 to 6 is such that the sliding bed section lies in horizontal planes in its raised and lowered positions. The bail is preferably movable clockwise into the position shown in Fig. 1 behind the false rail 27 and counter-clockwise into the position shown in Fig. 2 so that the removable mattress will not rest on it in either position. By using links 41 of greater length than that of links 42, the legs 35 and 36 will be swung through equal arcs and the sliding bed section will lie in horizontal planes in both lowered and raised positions.

As shown in Fig. 5, I may use this invention with a sofa provided with a back and no arms or as shown in Fig. 6 with a sofa or couch with neither back nor arms.

In Figs. 7 and 8 I have disclosed my invention modified for use with a sofa in which the platform is inclined to the rear for sitting comfort. In this case the end rails as indicated by 12 are inclined to the rear and in order to have the sliding bed section fit beneath the sofa, it is also inclined to the rear at the same angle to the horizontal. This may be effected by locating the pivot pins 60' Figs. 7 and 8 closer to the pivots 38 of the front legs 35 causing the rear legs 36 to be raised higher than the front legs 35 when the bed is lowered by swinging the bail 44 to the right. This shifting of the pivot pins 60' does not materially affect the angular relation of the legs 35 and 36 with the vertical when the bed is raised so that the bed will still lie substantially in a horizontal plane when in raised position. In this construction the links 41 and 42 may be made of the same length if desired and the amount of inclination of the sliding bed section may be controlled by the position of the pivot pins 60'. The organization is such that the bed inclines to the rear in its lowered position if the pivot pins 60' are placed midway between the pivots 38. The amount of inclination may be increased by shifting the pivot pins 60' to the right in Figs. 7 and 8.

While I have described my invention with particularity, it is to be understood that I reserve the right to use all changes thereof that fall within the principles of my invention and the scope of the appended claims.

I claim:

1. The combination with a bed frame, of legs pivoted thereto on pivots extending lengthwise of the frame for movement toward and away from each other, an operating bail pivoted on the ends of said frame, and linkage connections between said bail and said legs whereby when said bail is swung in one direction it will swing said legs toward each other to lower said frame and when swung in the opposite direction it will swing said legs away from each other to raise said frame, said bail operating to move said legs away from each other beyond the vertical, said

frame limiting the movement of said bail in either direction and said bail being adapted to engage a mattress on said frame to limit its movement in a direction to lower the frame.

2. The combination with a bed frame, of legs pivoted to the frame adjacent the four corners thereof on pivots extending lengthwise of the frame, and means for swinging said legs apart to raise said frame and toward each other to lower said frame, said means operating to swing the legs on one side of the frame closer to the frame than the legs on the other side of the frame, the construction being such that the frame will be in a horizontal position when raised and an inclined position when lowered.

3. The combination with a bed frame, of supporting legs pivoted thereto for movement away from each other beyond the vertical to support the frame in raised position and for movement

toward each other to support the frame in lowered position, and means for swinging said legs to cause the legs on one side of the frame to swing higher than the legs on the other side of the frame are swung whereby the frame will be inclined toward one side when lowered, said frame being also supported on said legs during swinging movement of said legs.

4. In combination with a bed frame, of legs pivoted on said frame adjacent its side edges and in one position supporting said frame in a horizontal plane, and means for swinging all of said legs toward said frame operating to swing the legs on one edge of said frame closer to said frame than the legs on the other edge of said frame to lower said frame into a plane inclined to the horizontal.

RUDOLPH O. SMITH.
